UNITED STATES PATENT OFFICE.

ALFRED DUNHILL, OF LONDON, ENGLAND.

RECEPTACLE FOR CIGAR OR CIGARETTE HOLDERS.

1,345,356.

Specification of Letters Patent.

Patented July 6, 1920.

Application filed June 10, 1919. Serial No. 303,082.

To all whom it may concern:

Be it known that I, ALFRED DUNHILL, a subject of the King of Great Britain and Ireland, residing at London, England, have 5 invented certain new and useful Improvements in and Relating to Receptacles for Cigar or Cigarette Holders, of which the following is a specification.

This invention relates to cigar and ciga-

10 rette holders and to cases for use therewith and refers more particularly to holders of the type in which the device is composed of two telescoping sections, so that it may be collapsed into a comparatively short length 15 or drawn out, to the full ordinary length, one of the sections constituting the holder portion proper and the other constituting the mouth piece.

The holder constructed according to my 20 present invention is adapted to be collapsed into a very small compass so that it can be packed in a special box or container which box or container may in some cases be made in the form of a charm or ornament to be 25 suspended from the watch chain or from a bracelet or the like.

In carrying out my invention I form the 30 holder from a plurality of, preferably from three or more tubular, slightly tapering sections, of approximately equal length, adapted to telescope with respect to one another, so that all the sections can be pushed down into the largest outer section or opened out 35 into a long rigid tapering tube.

The sections may be of gold, silver or 40 other material or combination of materials. For instance, the largest or holder section and the intermediate section constituting the mouth piece is of amber, tortoise shell 45 or the like.

The mouth piece section is provided with an enlarged end of sufficient size to prevent the sections coming apart when the article is collapsed.

45 In some cases the amber or other mouth piece thus provided with an enlarged end, may be screwed into a gold or other band constituting part of the innermost section, or this mouthpiece with an enlarged end 50 may constitute the section or some other equivalent construction may be provided.

The container, for the holder, which 55 container constitutes an important feature of my invention is of cylindrical shape and of a size sufficient to accommodate the holder when collapsed, and it is provided with

means for engaging the outermost section of the collapsed holder in such a way that when the holder is in position within the container and it is desired to withdraw the 60 same for use, upon taking hold of the innermost or mouthpiece section and drawing it out, the holder itself is automatically drawn into the extended position as it leaves the container.

65

And in order that my said invention may be clearly understood, I will now proceed to describe the same with reference to the accompanying drawing, which shows to an enlarged scale a cigarette holder and case 70 constructed according to my present invention and adapted to be suspended as a charm from the watch chain, a bracelet or the like.

Figure 1 shows the container closed. 75

Fig. 2 shows the container open with the telescoping holder drawn out ready for removal from the container.

Fig. 3 shows a similar view to Fig. 2 but with the cover of the container open and 80 showing the holder replaced and telescoped down.

The same letters of reference are employed to denote the same parts in all the views.

85

a is a cylindrical box of gold or other suitable material provided with a hinged cover *a*¹ and a ring *a*² for suspending it from the watch chain or other article.

The cigarette holder is in the present instance composed of four sections *b*, *b*¹, *b*² and *b*³.

The three sections *b*¹, *b*² and *b*³ are formed from slightly tapering tubes, of gold or other suitable material, while the section *b* constituting the mouth piece is formed of amber or the like, and is provided with an enlarged end *c* of sufficient size to prevent the sections coming apart when the holder is collapsed down so that the mouth piece 100 comes in the center and the sections *b*¹, *b*² and *b*³ are surrounding it.

At the bottom of the box *a* is a spring lip *d* and the upper edge of the box is cut away at *e* for the purpose hereinafter mentioned. 105

The operation will be readily understood. On opening the box *a* the cigarette holder is in the collapsed position with the mouth piece section *b* in the center and with the enlarged portion *c* projecting somewhat.

110

The mouth piece is pulled upward, the cut away portion *e* facilitating the grasp-

ing of the mouth piece between the finger and thumb. In this way the holder is drawn into the position shown in Fig. 2.

The lower end of the section b^2 is gripped 5 with sufficient force between the spring lip d and the wall of the box a to hold the said section in position while the tube is being drawn into the extended position, after which on further pulling upon the tube, the 10 section b^3 leaves the box a and the tube is ready for use.

Conversely when restoring the tube to the box, the section b^3 is inserted and in order 15 to cause the holder to come into the collapsed position sufficient force has to be used to reengage the bottom of the section b^3 between the spring lip d and the casing a .

It will be understood that the device may 20 be modified in various ways without departing from the principle of the invention. For instance a different type of spring means may be provided within the box or casing a for holding the outermost section in position, with sufficient force to cause the 25 device to be drawn into the extended position as it leaves the box.

What I claim as my invention and desire 30 to secure by Letters Patent of the United States of America is:—

30 1. A device of the character described for receiving the telescopic sections of a holder in collapsed form, comprising a container of greater diameter than the largest section of the holder and having means therein for 35 frictionally engaging said section only of

the holder and causing the holder to be brought into extended position simultaneously with the withdrawal thereof from the container, substantially as described.

2. A device of the character described for 40 receiving the telescopic sections of a holder in collapsed form, comprising a container of greater diameter than the largest section of the holder and having means therein for frictionally engaging said section only of 45 the holder and causing the holder to be brought into extended position simultaneously with the withdrawal thereof from the container, said container having a cut-away portion in the upper edge thereof to 50 facilitate the withdrawal of the holder, substantially as described.

3. The combination with a holder and 55 container therefor, in which the holder comprises a plurality of tapering sections adapted to telescope with respect to one another so that the device can be collapsed within the container with the smallest section coming within the next larger section, and having an enlarged portion thereon projecting 60 above the container, and means within the container for engaging the largest section only of the holder and causing the holder to be simultaneously drawn into extended position as the enlarged portion thereof is 65 grasped and withdrawn from the container, substantially as described.

In testimony whereof I have hereunto subscribed my name.

ALFRED DUNHILL.
